United States Patent Office

Des. 221,760
Patented Sept. 7, 1971

221,760

SHOWER ENCLOSURE WALL UNIT

Norman Van Skyhawk, Salt Lake City, Utah, assignor to
American Standard Inc., New York, N.Y.

Filed May 21, 1969, Ser. No. 17,250

Term of patent 14 years

Int. Cl. D23—02

U.S. Cl. D23—49

Fig. 1.

Fig. 2.

Fig. 3.

FIG. 1 is a front perspective view of a shower enclosure wall unit showing my new design.

FIG. 2 is a top plan view thereof.

FIG. 3 is a cross-sectional view taken on lines 3—3 of FIG. 2.

The broken line representation of a bathtub in FIGS. 1 and 3 is for purposes of illustration only.

I claim:

The ornamental design for a shower enclosure wall unit, as shown and described.
